INJECTION PUMP

Ulrich Aldinger, Stuttgart, Germany, assignor to Robert Bosch G.m.b.H., Stuttgart, Germany

Application April 16, 1958, Serial No. 729,015

Claims priority, application Germany April 17, 1957

11 Claims. (Cl. 103—37)

The present invention relates to injection pumps.

As is well known, injection pumps are used with internal combustion engines for supplying fuel to the cylinders of the engine to be burned therein.

At the present time certain types of injection pumps have certain disadvantages. For example, in certain types of pumps it is not possible to vary the cross section of the paths through which the fuel flows in the pump, so that the pumps are not as flexible and cannot adapt themselves readily to different operating conditions. Also, the leakage losses of the known injection pumps are unfavorable and the pumps are not capable of controlling the amounts of fuel delivered to the cylinders with the high degree of precision by which is desired. Moreover, in injection pumps which are known at the present time the reciprocating masses are larger than desired.

One of the objects of the present invention is to overcome the above drawbacks by providing an injection pump which is capable of being adjusted so as to regulate the cross section of passages through which fuel flows in the pump.

Another object of the present invention is to reduce undesirable leakage losses as well as to reduce the size of reciprocating masses, as compared to known injection pumps.

Also, it is an object of the present invention to provide an injection pump which can produce very precisely regulated amounts of fuel to be delivered to the engine.

Furthermore, it is an object of the present invention to provide an injection pump composed of simple and ruggedly constructed elements which are very reliable in operation.

With the above objects in view the present invention includes in an injection pump an elongated hollow first pump member and a first guide means guiding the first pump member for reciprocating axial movement between a suction dead center position, at the end of the suction stroke of the first pump member, and a pressure dead center position, at the end of a pressure stroke of the first pump member. A second hollow elongated pump member is provided with an interior which defines at least part of a pumping chamber, and this second pump member has an open end directed toward the first pump member and communicating with the pumping chamber formed in part at least by the interior of the second pump member. A second guide means guides the second pump member for axial reciprocating movement and positions the second pump member in the path of movement of the first pump member from its suction dead center position to its pressure dead center position so that during movement of the first pump member toward its pressure dead center position it engages and moves the second pump member, and the open end of this second pump member is closed by the first pump member when the latter engages the second pump member. An urging means such as a spring cooperates with the second pump

2

member for urging the same toward the first pump member, and in accordance with the present invention a stop means is provided to limit the movement of the second pump member by the urging means toward the first pump member to an end position where the second pump member is spaced from the first pump member while the latter continues to move to and from its suction dead center position so as to provide between the pump members a gap through which fuel flows into and out of the pumping chamber.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 shows a partly schematic axial sectional view of an injection pump constructed according to the present invention, the parts being shown in Fig. 1 at the suction dead center position of the pump; and

Fig. 2 fragmentarily illustrates the structure of Fig. 1 and shows the parts at the pressure dead center position.

Referring to Fig. 1, it will be seen that the injection pump illustrated therein includes an elongated hollow pump member 3 which also functions as a distributor in that this elongated hollow pump member 3 is formed with an opening 33 passing through its wall and communicating through passages described below with the several cylinders of the engine. This elongated hollow pump member 3 cooperates with the second elongated hollow pump member 4 which is coaxial with the pump member 3 and which has a hollow interior defining part of a pumping chamber. It will be noted that the bottom end of the pump member 4, as viewed in Figs. 1 and 2, which is directed toward the pump member 3 is open.

The elongated hollow pump member 3 is connected at its bottom end, as viewed in Figs. 1 and 2, with a drive 40 which both rotates and axially reciprocates the pump member 3. As is diagrammatically shown in Fig. 1, the injection pump includes a plurality of rollers 10 which are supported for rotation about stationary axes, respectively, and a drive shaft 5 is rotated and is fixed 45 with a cam 7 having downwardly directed camming portions which cooperate with the rollers 10 so that during rotation of the drive shaft 5 the latter together with the cam 7 reciprocate as well as rotate, the reciprocation resulting from the cooperation of the downwardly directed 50 annular camming surface of the cam 7 with the rollers 10. The cam 7 reciprocates during each of its revolutions a number of times equal to the number of cylinders of the engine.

The elongated hollow pump member 3 carries at its 55 bottom end a cross pin 6 which extends transversely through and beyond the pump member 3, and the free ends of the cross pin 6 which are respectively located laterally beyond the exterior surface of the hollow pump member 3 are respectively located in a pair of notches 60 formed in the cam 7. A ring 12 retains the pin 6 in the notches of the cam 7 and a snap ring 13 which is located in an annular groove of the cam 7 retains the ring 12 in engagement with the cross pin 6, so that in this way the latter is maintained in the notches and thus 65 serves to connect the pump member 3 to the cam 7 for axial and rotary movement therewith.

The injection pump includes a support or housing 1, and a spring 8 is coiled about the pump member 3 and bears with its top end against a surface of the stationary support 1. At its bottom end the spring 8 bears against the race ring of a thrust ball bearing 9, so that the spring 8 serves to maintain the cam 7 in engagement with the

rollers 10 while at the same time freeing the cam 7 for rotation with respect to the spring 8.

A plug 14 is pressed into the bottom end of the elongated hollow pump member 3, as viewed in Figs. 1 and 2, and this plug 14 is formed with a transverse bore through which the pin 6 passes. The plug 14 fixedly carries at its top surface a rod 18 which extends axially along the interior of the hollow pump member 3, and a coil spring 15 is coiled about this rod and bears with its bottom end against the plug member 14. At its top end the spring 15 bears against a valve member 16 which is pressed by the spring 15 into engagement with a valve seat formed by an annular shoulder in the interior of the elongated hollow pump member 3, this valve member 16 being formed with a plurality of radial elongated fins above the portion of the valve member which engages the valve seat, so that when the valve member 16 is located in the pump member 3 at a position below the valve seat of the pump member 3 the fuel may flow past the valve member 16 axially along the interior of the pump member 3. The rod 18 limits the extent of opening movement of the valve member 16, and when the latter valve member is in a valve opening position the fuel may flow to the opening 33 of the pump member 3, and from this opening 33 the fuel is distributed to the several cylinders. Above the valve seat which cooperates with the valve member 16 the elongated hollow pump member 3 is formed with a plurality of openings 24 which pass through the wall of the pump member 3 and which communicate at their outer ends with an annular groove 29 formed in the exterior surface of the pump member 3.

A suitable guide means is provided for guiding the pump member 3 for axial reciprocating movement, and this guide means includes an elongated hollow cylindrical member 72 having an interior surface which is directed toward an exterior surface of the pump member 3. The exterior surface of the pump member 3 is slidably along the interior surface of the cylindrical guide member 72. This guide member 72 is formed with a plurality of openings 73 corresponding to the number of cylinders and distributed about the axis of the cylindrical guide member 72, so that during the rotary and reciprocating movement of the member 3 the opening 33 thereof successively communicates with the several openings 73 so as to deliver fuel thereto. These openings 73 respectively communicate with passages 74 which respectively lead to the several cylinders, so that in this way the fuel is delivered by the injection pump to the several cylinders. One of the passages 74 is illustrated in Fig. 1.

The cylindrical guide member 72 is furthermore formed with a plurality of overflow openings 75 which cooperate with the annular groove 29 of the pump member 3. The cylindrical guide member 72 is carried by the support 1 and has an exterior surface directed toward and located next to an interior surface of the support 1, and one of these surfaces is formed with a plurality of passages 77 which respectively communicate with the overflow openings 75. In the particular example illustrated in the drawings, the exterior surface of the cylindrical guide member 72 is formed with the axial grooves 77 which respectively extend downwardly from the overflow opening 75 into the low pressure chamber of the injection pump which houses the spring 8. This low pressure chamber of the injection pump which houses the spring 8 as well as the cam drive communicates through a conduit 78 with the supply tank 35 from which fuel is pumped to the injection pump by a supply pump 36.

The second elongated hollow pump member 4 is also guided by a suitable guide means for axial reciprocating movement, and this guide means includes an elongated sleeve 25 which has located in its interior an end plate 26 which cooperates with the upper end of a spring 27 located in the interior of the member 4 which defines the

pumping chamber 31 and forming an urging means for urging the pumping member 4 toward the pump member 3. The bottom end of the spring 27 bears against an inner annular shoulder of the pumping member 4 for urging the latter downwardly toward the pump member 3. The guide member 25 is guided itself in the interior of the housing 1 by an inner cylindrical surface thereof located next to the plug 30, and the spring 27 maintains the top wall of the guide member 25 in engagement with the bottom surface of the plug 30, as viewed in Fig. 1.

In accordance with the present invention an adjustable stop means is provided for limiting the movement of the pump member 4 toward the pump member 3, both of these pump members being coaxial. This stop means includes an elongated hollow sleeve 87 having at its bottom end an inwardly directed annular flange 89 which is engaged by an outwardly directed annular flange 90 of the pump member 4 so as to limit the movement of the pump member 4 by the spring 27 to an end position of the pump member 4 which is illustrated in Fig. 1. The flange 89 is formed with an upwardly directed frustoconical surface engaged by a downwardly directed frustoconical surface of the flange 90, and these frustoconical surfaces mate with each other and form a fluid-tight engagement between the pump member 4 and the stop member 87.

At its open end which is directed toward the pump member 3, the pump member 4 is formed with a second frustoconical annular surface 92 which is separated from the flange 90 by an annular cutout 91 formed at the exterior of the pump member 4, and this frustoconical surface 92 at the open end of the pump member 4 which is directed toward the pump member 3 cooperates with a frustoconical surface 93 located at the top end of the elongated hollow pump member 3, and the frustoconical surface of flange 90 as well as the frustoconical surface 92 of the pump member 4 form part of the same cone. The surfaces 92 and 93 also have a fluid-tight engagement with each other, so that the cooperation of the flange 90 with the flange 89 serves to separate the inlet pump chamber 95 from the space 94 defined between the stop member 87 and the pump member 4, while the cooperation of the surfaces 92 and 93 with each other serves to separate the pump chamber 31 from the inlet chamber 95 and the space 94.

As is apparent from Fig. 1, the limiting of the movement of the pump member 4 by the stop member 87 to the end position of the pump member 4 shown in Fig. 1 provides at the suction dead center position of the pump member 3, which is illustrated in Fig. 1, a gap between the pump members 3 and 4, and the fuel under pressure in the inlet chamber 95 of the pump can flow from this inlet chamber 95 through the gap between pump members 3 and 4 into the pumping chamber 31 through the open end of the pump member 4 which is directed toward the pump member 3. In accordance with the present invention an adjusting means cooperates with the stop means provided by the sleeve 87 for adjusting the position of the latter along the axis of the pump member 3, so that in this way the size of the gap between the pump members 3 and 4 at the suction dead center position of the pump member 3 may be regulated. This adjusting means includes a pin 98 which extends into an opening of the sleeve 87, and this pin 98 is fixed eccentrically to the left end of a rod 100 provided intermediate its ends with a collar 101 fixed to the rod 100 and pressed against a sealing ring 103 by a sleeve member 102 which is threaded carried by the support 1 in the manner shown in Fig. 1, this sleeve 102 supporting the rod 100 for turning movement about its axis. A lever 99 is fixed to the outer end of the rod 100, so that by turning the lever 99 the eccentric pin 98 will turn to regulate the elevation of the stop member 87. This stop member 87 is capable of turning about its axis during turn-

ing of the eccentric pin 98 about the axis of the rod 100, and there is sufficient clearance of the pin 98 in the opening of the sleeve 87 to prevent any binding between these elements during turning of the rod 100 about its axis. Thus, it is possible with this structure to adjust the maximum size of the gap between members 3 and 4. As is evident from Fig. 2 which shows the pump member 3 at its pressure dead center position, this pump member 3 during its pressure stroke approaches and engages the pump member 4 to move the latter axially against the force of the spring 27, while during movement of the pump member 3 from the position of Fig. 2 toward the position of Fig. 1 the pump member 4 will be engaged by the stop member 87 to prevent continued movement of the pump member 4 with the pump member 3 while the latter continues to move to and from the suction dead center position thereof shown in Fig. 1. The lever 99 is connected through any suitable linkage to a manually engageable member so that the operator may turn the lever 99 through this linkage in order to adjust the elevation of the sleeve 87.

As was pointed out above, the pump 36 draws the fuel from the tank 35, and this pump 36 pumps the fuel under pressure through a filter 37 to a supply conduit 43 which supplies the fuel to the injection pump, the excess fuel flowing through an overflow valve 39 from the filter 37 back to the tank 35. The conduit 43 delivers the fuel to a passage 109 of the injection pump, and this passage 109 communicates through a passage 110 with the inlet chamber 95 referred to above. The cross section of the passage 110 may be regulated by an axially movable pin 112 which is guided for axial movement by suitable bores of the housing 1 and which extends across the interior of the passage 110. In the passage 110 the pin 112 is provided with an annular V-shaped groove, so that by varying the axial position of the pin 112 the cross sectional area of the passage 110 through which the fuel flows may be regulated, and in this way an adjustable throttle for the supply of the fuel to the inlet chamber 95 is provided. The throttle member 112 separates the passages 109 and 110 from each other, and the throttle member 112 is guided in the axial bore 113 of the housing 1, this bore 113 being closed at its top end, as viewed in Fig. 1, by a plug 114 which cooperates with a sealing ring 115. At its bottom end, as viewed in Fig. 1, which extends into the interior of the injection pump, the throttling rod 112 is connected in a known way with a governor which may be adjusted by the operator at will so as to regulate the position of the rod 112.

As is shown in Fig. 1, the space 94 between the pump member 4 and the stop member 87 communicates through a passage 117 with the passage 109 to which the fuel is delivered from the conduit 43.

Thus, when the pump member 3 moves along its suction stroke to the position of the pump member 3 shown in Fig. 1, there comes a time when the pump member 4 is prevented from moving with the pump member 3 by engagement with the flange 89, and at this time the fuel flows from the inlet chamber 95 into the pumping chamber 31. At the beginning of the pressure stroke of the pump member 3, the volume of the inlet chamber 95 is reduced by the movement of the pump member 3 until the latter engages the pump member 4, and this increase in the pressure of the fuel in the inlet chamber 95 which communicates with the pump chamber 31 is of advantage since it enables the upper speed limit to be raised, this upper speed limit being determined by the pressure of the fuel in the pump chamber 31 during the filling of this pump chamber.

As soon as the pump member 3 moves the pump member 4 away from the flange 89, the pump chamber 31 is closed and the valve 16 then opens due to the diminishing volume of the pump chamber 31 and the corresponding pressure which serves to open the valve member 16

against the force of the spring 15, so that the fuel then flows to the distributor opening 33 of the pump member 3 to be delivered from the opening 33 successively through the several cylinders through the several passage means 73, 74. The delivery of the fuel from the pump member 3 to a particular cylinder at any given moment continues until the continued movement of the pump member 3 along its pressure stroke places the annular groove 29 in engagement with the overflow openings 75.

- 10 At this time the fuel can flow from the interior of the pump member 3 through the overflow opening 75 and along the grooves 77 to the low pressure chamber which communicates through the conduit 78 with the tank 35, so that when the groove 29 communicates with the overflow opening 75 the delivery of the fuel to a given cylinder of the engine stops. Because of the drop in pressure provided in the interior of the pump member 3 at the moment when the groove 29 communicates with the overflow opening 75, the spring 15 returns the valve 16 to its closed position, and any fuel remaining in the pump member 3 from this moment on during the continued movement of the pump member 3 simply flows through the overflow openings back to the tank 35. Moreover, during the pressure stroke of the pump 3, from the moment that this pump member 3 engages the pump member 4 and moves the latter away from the flange 89, the volumes of the inlet chamber 95 and the space 94 are also reduced, and the fuel displaced from the chamber 95 and the space 94 in this way flows through the passage 117 back to the inlet passage 109. This passage 117 provides for the return flow of the fuel at smaller resistance than the passage 110 with the throttling member 112.

The above operations take place during the pressure stroke of the pump. During the succeeding suction stroke, which is to say during the return of the parts from the positions of Fig. 2 to the position of Fig. 1, fuel is sucked through the passage 117 from the passage 109 into the space 94 and chamber 95 until the flange 90 of the pump member 4 engages the flange 89 of the stop member 87 so as to separate the space 94 from the inlet pump chamber 95. Then, during the continued movement of the pump member 3 by itself along its suction stroke to the suction dead center position thereof shown in Fig. 1, the fuel flows through the passages 109 and 110 past the throttling member 112 into the inlet chamber 95 from where the fuel flows into the pumping chamber 31 through the gap between the pump members 3 and 4. The engagement of the flange 90 with flange 89 provides the further advantage of separating the space 94 from the chamber 95 so as to greatly reduce the free space in the interior of the pump to which fuel under pressure is delivered, this space being limited only by the passage 110 and the inlet chamber 95.

By actuation of the lever 99, it is possible for the operator to position the stop member 87 during starting of the engine at a location which permits the engine to be provided at starting thereof with amounts of fuel which exceed the full load amounts, so that the engine can be properly started.

The adjustment of the amounts of fuel delivered by the pump during the operation of the engine according to the loading thereof is provided with the aid of the throttling member 112. According to the axial position of this throttling member, the cross sectional area of the passage 109, 110 is increased or decreased. The smaller this cross sectional area the smaller the amount of fuel which can flow through the gap between members 3 and 4 during the suction stroke of member 3, the length of time of this suction stroke being determined by the speed of the engine.

It will be understood that each of the elements described above, or two or more together, may also find a useful application in other types of injection pumps differing from the types described above.

While the invention has been illustrated and described as embodied in adjustable injection pumps, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position while the first pump member continues to move to and from its suction dead center position so as to provide between said pump members a gap; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

2. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial movement and positioning said second pump member coaxially with said first pump member in the path of movement of the latter from its suction dead center position to its pressure dead center position so that during movement of said first pump member toward its pressure dead center position it engages and moves

5 said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

20 3. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed; and adjusting means cooperating with said stop means for adjusting the position thereof along the axis of said first pump member, so that the maximum size of said gap may be adjusted and so that the moment during the pressure stroke of said first pump member that the latter engages said second pump member and the moment during the suction stroke of said first pump member that the latter leaves said second pump member may be adjusted.

25 4. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging

said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap, said stop means having an annular frustoconical surface engaged by said second pump member and the latter having an annular frustoconical surface mating with and engaging said annular surface of said stop means; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

5. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member; a second open end; second guide means surrounding and slidably engaging said second pump member and having a closed end spaced from said second open end of said second hollow elongated pump member and defining a pumping chamber, said second guide means guiding said second pump member for axial movement and positioning said second pump member coaxially with said first pump member in the path of movement of the latter from its suction dead center position to its pressure dead center position so that during movement of said first pump member toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; and stop means limiting the movement of said second pump member by said urging means toward said first pump member to an end position where said second pump member is spaced from said first pump member while the latter continues to move to and from its suction dead center position so as to provide between said pump members a gap, said stop means having an annular frustoconical surface engaged by said second pump member and said second pump member having an annular frustoconical surface mating with and engaging said annular surface of said stop means when the latter locates said second pump member in said end position thereof, and said first pump member having an annular frustoconical surface and said second pump member having an annular frustoconical surface located at said open end thereof and engaging said annular frustoconical surface of said first pump

member when the latter is in engagement with said second pump member; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

6. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial movement and positioning said second pump member coaxially with said first pump member in the path of movement of the latter from its suction dead center position to its pressure dead center position so that during movement of said first pump member toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap, said stop means having an annular frustoconical surface engaged by said second pump member and said second pump member having an annular frustoconical surface mating with and engaging said annular surface of said stop means when the latter locates said second pump member in said end position thereof, and said first pump member having an annular frustoconical surface and said second pump member having an annular frustoconical surface located at said open end thereof and engaging said annular frustoconical surface of said first pump member when the latter is in engagement with said second pump member, said first-mentioned and second annular frustoconical surfaces of said second pump member forming part of the same cone; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

7. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial movement and positioning said second pump member co-

axially with said first pump member in the path of movement of the latter from its suction dead center position to its pressure dead center position so that during movement of said first pump member toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap through which fuel flows into and out of said pumping chamber, said stop means having an annular frustoconical surface engaged by said second pump member and said second pump member having an annular frustoconical surface mating with and engaging said annular surface of said stop means when the latter locates said second pump member in said end position thereof, and said first pump member having an annular frustoconical surface and said second pump member having an annular frustoconical surface located at said open end thereof and engaging said annular frustoconical surface of said first pump member when the latter is in engagement with said second pump member, said first-mentioned and second annular frustoconical surfaces of said second pump member forming part of the same cone, said second pump member being formed with an annular cutout located between and separating said first-mentioned and said second annular frustoconical surfaces of said second pump member from each other; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

8. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap through which fuel flows into and out of said pumping chamber, said stop means having an annular frustoconical

5 surface engaged by said second pump member and said second pump member having an annular frustoconical surface mating with and engaging said annular frustoconical surface of said stop means when the latter locates said second pump member in said end position thereof, said annular frustoconical surfaces of said stop means and said second pump member having a fluid-tight engagement with each other; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

9. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said first pump member and a second open end; second guide means surrounding and slidably engaging said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap through which fuel flows into and out of said pumping chamber, said stop means and said second pump member defining between themselves a space which surrounds said second pump member and is located between the latter and said stop means; means forming an inlet chamber of said injection pump to which fuel under pressure is supplied from a supply pump; passage means providing communication between said space and said inlet chamber; and valve means communicating with said pumping chamber to discharge fuel therefrom during said pressure stroke of said first pump member after said gap is closed.

10. In an injection pump having a low pressure chamber, in combination, a cylindrical guide member having an exterior surface and formed with a plurality of overflow openings passing through the wall of said cylindrical guide member; a support supporting said guide member and having an inner surface located next to and directed toward said exterior surface of said guide member, one of said surfaces being formed with a plurality of grooves respectively leading from said overflow openings of said guide member to a low pressure chamber of the injection pump; a first elongated hollow pump member slidably guided for reciprocating axial movement by said guide member in the interior thereof and being formed in its wall with a plurality of passages communicating with said overflow openings of said guide member during a predetermined part of the axial movement of said first pump member, said guide member guiding said first pump member for movement between a suction dead

center position, at the end of a suction stroke of said first pump member, and a pressure dead center position, at the end of a pressure stroke of said first pump member; a second hollow elongated pump member having a first open end directed toward said first pump member and a second open end; guide means surrounding and slidably engaging said second pump member and having a closed end spaced from said second open end of said second hollow elongated pump member and defining a pumping chamber, said guide means guiding said second pump member for axial reciprocating movement and positioning said second pump member in the path of movement of said first pump member from its suction dead center position to its pressure dead center position so that during movement of said first pump member toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap; fluid inlet means communicating with said gap through which fluid may flow into said pumping chamber when said second pump member is in said end position; and valve means communicating with said pumping chamber to discharge fluid therefrom during said pressure stroke of said first pump member after said gap is closed.

11. In an injection pump, in combination, an elongated hollow first pump member; first guide means guiding said first pump member for reciprocating axial movement between a suction dead center position, at the end of a suction stroke of said first pump member, and a pressure dead center position, at the end of a pressure stroke of said first pump member; a second hollow elongated pump member having a first open end directed toward said

first pump member and a second open end; second guide means surrounding and slidably engaging said second pump member and having a closed end spaced from said second open end of said second hollow elongated pump member and defining a pumping chamber, said second guide means guiding said second pump member for axial reciprocating movement and positioning said second pump member in the path of movement of said first pump member from its suction dead center position to its pressure dead center position so that during movement of said first pump member along its pressure stroke toward its pressure dead center position it engages and moves said second pump member toward said closed end to provide for a pumping action, the first open end of the latter being closed by said first pump member when the latter engages said second pump member; urging means cooperating with said second pump member for urging the latter toward said first pump member; stop means limiting the movement of said second pump member by said urging means toward said first pump member to an end position where said second pump member is spaced from said first pump member while the latter continues to move to and from its suction dead center position so as to provide between said pump members a gap; means forming a fuel inlet chamber of said injection pump communicating said gap so that fuel under pressure in said inlet chamber of said pump flows through said gap into said pumping chamber; adjustable means cooperating with said inlet chamber for regulating the cross sectional area thereof; and valve means communicating with said pumping chamber to discharge fuel therefrom during said pressure stroke of said first pump member after said gap is closed.
